AIRBRUSH

Jens A. Paasche, Chicago, Ill.

Application February 4, 1943, Serial No. 474,664

4 Claims. (Cl. 299—88)

This invention relates generally to air brushes and more particularly to air brushes adapted for use in art work.

Air brushes of the type contemplated by the present invention must be capable of efficient performance in the hands of the beginner as well as in the hands and under the exacting eye of the expert. In addition to being efficiently operable, such brushes must also be capable of being economically produced. Therefore, the constituent parts must be simple yet rigid in construction and the brush must have features of adjustment which will render it adaptable for efficient operation in performing a wide variety of art work requiring execution of finest detail work with colors of light or heavy consistency.

The present invention relates more specifically to certain improvements in the design of air brushes, and it is one of the important objects of the present invention to provide an air brush structure wherein the pigment receptacle may be secured in various positions of adjustment to accommodate its use to various positions in which the handle of the air brush is held when in use.

It is also an object of the present invention to provide an air brush of the type set forth above which will operate very silently and to this end the invention contemplates an improved actuator wheel construction capable of receiving a blast of air at its periphery without causing any appreciable noise to be developed.

It is another object of the present invention to provide in association with an air brush structure capable of manual manipulation, improved guiding means for a reciprocable pigment conveying needle and also improved means for laterally adjusting the position of the needle, whereby to enhance operating efficiency and to facilitate both repair and replacement of parts.

The invention contemplates an air brush structure in which the constituent parts are relatively few in number and whereby both adjustment, repair and replacement may be accomplished with a minimum amount of skill and effort on the part of the user and whereby the device may be very economically manufactured.

The foregoing and other objects and advantages will be more apparent from the following detailed description when considered in connection with the accompanying drawings, wherein:

Fig. 1 is a plan view of an air brush embodying features of the present invention, one extremity of the handle thereof being broken away to more clearly illustrate the manner in which a supply of needles may be retained within the handle structure;

Fig. 2 is an enlarged fragmentary longitudinal sectional view taken substantially along the line 2—2 of Fig. 1;

Fig. 3 is an enlarged end sectional view of the

device, said view being taken substantially along the line 3—3 of Fig. 1;

Fig. 4 is an enlarged sectional view of the needle guiding bushing and support therefor taken substantially along the line 4—4 of Fig. 5;

Fig. 5 is an enlarged plan sectional view taken substantially along the line 5—5 of Fig. 2 with portions of the pigment receptacle support and the air directing nozzle associated with the reciprocable needle being shown in section for the purpose of clearness;

Fig. 6 is an enlarged detailed sectional view of the air operated actuating wheel and housing therefor taken substantially along the line 6—6 of Fig. 5;

Fig. 7 is an enlarged fragmentary detailed sectional view taken transversely of the handle structure substantially along the line 7—7 of Fig. 2;

Fig. 8 is also a detailed transverse sectional view taken substantially along the line 8—8 of Fig. 3 to more clearly illustrate the arrangement of the adjustable needle guiding element and supporting structure associated therewith;

Fig. 9 is a fragmentary side elevational view of the lower or forward extremity of the air brush structure to illustrate the position occupied by the adjustable pigment receptacle when used in association with a surface slightly inclined from the horizontal; and

Fig. 10 is a view similar to Fig. 9 disclosing an adjusted position of the pigment receptacle when the air brush is used in association with a surface slightly inclined from the vertical.

Referring now to the drawings wherein like numerals have been employed to designate similar parts throughout the various figures, it will be seen that one embodiment of the invention as disclosed herein contemplates a handle structure designated generally by the numeral 12. The

left extremity of the handle structure 12 carries an air operated actuating wheel 14. The lower side of the wheel 14 carries a bearing member 16 (Fig. 6) which is adapted to revolve within a complementary hardened bearing member or sleeve

18. The bearing member 18 is carried by a frame or housing structure 20 which cooperates with a cover or complementary housing structure 22 in enclosing the actuating wheel 14 and the bearing elements associated therewith. Extending upwardly from and secured to the wheel 14 is an eccentric crank member 24 and projecting upwardly from the upper side of the crank 24 is a bearing member 26 which is capable of rotation within a complementary bearing member 28 centrally disposed within the housing or cover member 22. The bearing members 16 and 26 present trunnions which cooperate with their respective complementary bearing members 18 and 28 in

55 rotatably supporting the wheel 14 within the housing structure. In fact, this bearing arrangement

60

ment is substantially frictionless due to the limited area of contact coupled with the fact that enclosed lubricant or grease retaining chambers 30 and 32 serve to continuously retain a supply of lubricant for said bearings. Threaded caps 34 and 36 are provided to enable replenishment of lubricant when required. Experience has shown that once the chambers 30 and 32 have been packed with grease, this servicing will suffice for practically the entire life of the brush.

A needle actuating member or arm 38 is provided with a longitudinal recess 40 through which the crank pin 24 extends. One extremity of the arm 38 is pivotally connected at 42 to one extremity of a reciprocable piston member 44. This piston member 44 is continuously urged to the right under the influence of a coil spring 46. The opposite extremity of the needle actuating member or arm 38 is provided with an elongated section having a slot 48 for receiving the bent over portion of a needle 50 (see Figs. 3 and 5). From the foregoing it will be apparent that rotation of the wheel 14 will effect oscillation of the arm 38 and consequent longitudinal reciprocation of the needle 50.

The pointed extremity of the needle 50 is actuated within a bushing member 52 (Figs. 4 and 5) carried by a support 54. The bushing 52 is readily removable for purposes of replacement, as will be clearly apparent from the drawings.

Extending beneath and in substantial parallelism with the needle 50 is an arm 56 (Figs. 3 and 5) which is formed rigidly with and extends tangentially from the lower casing or frame structure 20. This arm 56 is provided with a recess 58 for accommodating and guiding the bent portion of the needle 50, as clearly shown in Fig. 3. The free extremity of the arm 56 is recessed at 60 to accommodate a receptacle supporting member 62 and is bifurcated so as to enable a screw member 64 (Figs. 3 and 8) when tightened to rigidly clamp the member 62 in place. The arm 56 also serves as a support for a needle guiding element 66. This member 66 is axially adjustable upon a threaded stud 68 and is provided with an inclined needle engaging and guiding surface 70. If the member 66 is adjusted downwardly from the position shown in Fig. 8, the needle 50 is shifted laterally to the left. Thus, the member 66 serves as a needle guiding means and also as means for controlling the path in which the needle reciprocates. That is to say, the surface 70 cooperates with the guiding bushing 52 in maintaining the needle in its proper path of reciprocation at all times. A coil spring 72 serves to frictionally maintain the member 66 in various positions of adjustment. Slight adjustments of the surface 70 may be made by rotatably engaging the knurled extremity of the member 66.

Attention is now directed to a pigment receptacle 14. This receptacle serves to retain a supply of pigment and the chamber of the receptacle communicates with the area in the vicinity of the bushing 52 through an aperture or conduit in a radially projecting member 76 which is enlarged at its free extremity to provide the bushing support or head 54. The free extremity of the arm 62 is secured to the radially projecting member 76 and thus serves as a support for the receptacle 14. It will be noted that the receptacle 14 may be tiltably adjusted about the axis of the member 62 by loosening the screw or stud 64. The purpose of this adjustment will be more apparent as the description progresses. It is important, however, at this point to note that tilt-

able adjustment of the receptacle 14 may be made about an axis substantially coincident with the axis of the needle 50 so that when such adjustment takes place no lateral displacement of the needle guiding bushing 52 will result.

A nozzle 78 which terminates adjacent the portion of the needle 50 which projects beyond the guide bushing 52 serves to direct an air blast across the needle after it has been supplied with pigment. A suitable needle valve 80 serves to control the amount of air passing through the nozzle 78. The nozzle 78 is connected to the handle structure 12 by a suitable coupling 82 (Figs. 1 and 5). Air is directed into the coupling 82 from a passage 84 within the handle structure 12 (Fig. 2). The air blast from this passage is also directed against the periphery of the wheel 14 through a conduit 86 (Figs. 2, 5 and 7). The air blast through this conduit 86 is controlled by a suitable needle valve 88. Control of air pressure directed against the actuating wheel 14 and the pointed extremity of the needle 50 is effected by the manual manipulation of a finger operated button 90.

This button 90 is so positioned that the user of the air brush in grasping the handle structure 12 may conveniently depress and tilt the button. Depending from the button 90 is a lever 92 which is pivotally supported in the outer bent extremity of a control rod 94. The portion of the lever 92 extending below the bent extremity of the rod 94 is adapted to engage the outer extremity of the piston member 44. As the button 90 is inwardly depressed, the downward movement of the control rod 94 causes a valve member 96 to be unseated, thereby permitting an air blast to be directed from a chamber 88 into the conduit or passageway 84. A spring 100 continuously urges the valve member 96 and actuating rod 94 outwardly so as to automatically close the valve against a gasket or seat 102 when pressure is released from the button 90. A suitable screen or filter 104 serves to remove all foreign elements from the air before it enters the chamber 98. An adjustable abutment screw 106 is mounted in the outer portion of the rod 94 and serves as a positive stop to limit the tilting of the button 90 to the left (Figs. 1 and 2). Thus, when the valve 96 is unseated by the downward movement of the control button 90, an air blast is directed against the periphery of the actuating wheel 14 through the conduit 86, and the nozzle 78 directs an air blast against the pointed extremity of the reciprocating needle. This air blast against the reciprocating extremity of the needle causes pigment to be removed in the form of a stream from the needle.

The quantity of pigment discharged from the needle may be regulated by oscillating the lever 92. Thus, by tilting the lever to the right from the position shown in Fig. 2 the piston 44 and consequently the actuating arm 38 is shifted to the left. This causes the needle 50 to experience a greater degree of reciprocation and consequently enables a larger quantity of pigment to be discharged from the pointed extremity of the needle. Thus, by slight tilting movement of the lever 92 a very fine control of the quantity of pigment may be obtained. Also the volume of air may be simultaneously controlled by downwardly depressing the button 90, as previously described. Further adjustment of air blast may be obtained by adjustment of the needle valves 80 and 88.

Attention is now directed to the specific ar-

angement of air receiving recesses or serrations 108 provided along the periphery of the wheel 14. It will be noted that these recesses are relatively shallow and completely traverse the relatively narrow width of the wheel. It has been found that the use of these relatively fine serrations enables the wheel to be air operated with substantially no noise. Thus, the wheel and its associated parts operate very silently and free from vibration.

In using the air brush just described the handle structure 12 is gripped similarly to the gripping of a writing pen. When the brush is to be used on a surface which is parallel to or slightly inclined from the horizontal as indicated in Fig. 9, the receptacle 74 is secured in the position shown. When the surface to be treated is positioned more nearly to the vertical, the handle structure is positioned as shown in Fig. 10 and a tiltable adjustment of the receptacle 70 may be made so as to retain said receptacle in a substantially horizontal position. Thus, regardless of the position in which the handle structure is held, while the brush is in use the receptacle may be adjusted so as to positively prevent spilling of pigment therefrom. This adjustment may be effected, as previously pointed out, by loosening the set screw 54 and then shifting the receptacle or cup to the desired position. This shifting is accomplished without disturbing the alignment of the removable bushing 52 from its support.

It will be noted that the needle valve 80 is secured in any position of adjustment through the agency of a coil spring 109, Fig. 5. The pressure of this coil spring against the under side of the screw head is sufficient to prevent inadvertent rotation thereof. To further protect the screw against inadvertent rotation, a suitable cap 111 is placed over the head of the screw, as illustrated in Fig. 5. This cap is disassociated from the other figures wherein the needle valve 80 appears merely for the purpose of more clearly illustrating the structural characteristics of the valve.

It will also be noted that the recess in the bearing member 18 for receiving the rotary pintle or bearing member 16 is relatively deep. This insures the wheel 14 against tilting out of alignment when the cover or housing structure 22 is removed. By maintaining the axis of the wheel in its upright position, the ease with which the cover may be reapplied and the bearing member 28 thereof registered with the complementary pintle or bearing 26 is greatly facilitated.

From the foregoing it will be apparent that the invention contemplates an air brush of extremely practical yet simple construction. The device is extremely easy to operate and the driven parts operate free from noise or vibration. The ease with which the reciprocating needle may be continuously maintained in proper alignment and the simplicity of the removable guide bushing 52 materially contributes to the efficient functioning of the brush. As shown in Fig. 1, the outer extremity of the handle structure is recessed to accommodate an extra supply of needles, it being only necessary to remove a cap 110 to permit access to the needles. The novel bearing arrangement for the actuating wheel as well as the novel peripheral construction of the wheel itself also renders the brush efficiently operable for an extended period of time without the necessity of adjustment, repair or replacement.

While a specific embodiment of the invention is disclosed in the drawings, it will be apparent that other modifications and changes are contem-

plated, and that the invention should not be limited thereby as is apparent from the scope of the appended claims.

The invention is hereby claimed as follows:

- 5 1. An air brush including an air operated actuating wheel having a relatively finely serrated periphery, an oscillatory needle actuating member driven by said wheel, means for directing an air blast against the serrated periphery of said wheel for actuating same, a needle connected with and longitudinally reciprocated by said oscillatory actuating member, guide means for said needle in the vicinity of the pointed extremity thereof, a pigment receptacle communicating with an area traversed by the pointed extremity of the reciprocable needle, angularly and longitudinally adjustable receptacle supporting means for securing said receptacle in various positions of adjustment to accommodate it to various positions in which the air brush is held when in use, means for directing an air blast to the pointed extremity of the needle after it has been supplied with pigment from the aforesaid area, a handle structure, and manually operable air blast control means carried by said handle structure.
- 10 2. An air brush as set forth in claim 1 wherein the guide means for the needle is carried as a unit with the pigment receptacle.
- 15 3. An air brush including an air operated actuating wheel, an oscillatory needle actuating member driven by said wheel, means for directing an air blast against the periphery of said wheel for actuating same, a needle connected with and longitudinally reciprocated by said oscillatory actuating member, guide means for said needle in the vicinity of the pointed extremity thereof, said guide means including a removable channelled bushing member and a support therefor, said bushing having an opening extending from adjacent the bottom of the channel to the exterior of said bushing for communication with a pigment receptacle, a pigment receptacle communicating with an area traversed by the pointed extremity of the reciprocable needle, means for directing an air blast to the pointed extremity of the needle after it has been supplied with pigment from the aforesaid area, a handle structure, and manually operable air blast control means carried by said handle structure.
- 20 4. An air brush including an air operated actuating wheel, an oscillatory needle actuating member driven by said wheel, means for directing an air blast against the periphery of said wheel for actuating same, a needle connected with and longitudinally reciprocated by said oscillatory actuating member, guide means for said needle in the vicinity of the pointed extremity thereof, a pigment receptacle communicating with an area traversed by pointed extremity of the reciprocable needle, adjustable receptacle supporting means for securing said receptacle in the various positions of adjustment to accommodate it to various positions in which the air brush is held when in use, said receptacle supporting means being so constructed and arranged as to permit tilting of the receptacle supported thereby about an axis substantially coincident with the axis of the needle, means for directing an air blast to the pointed extremity of the needle after it has been supplied with pigment from the aforesaid area, a handle structure, and manually operable air blast control means carried by said handle structure.
